1

My invention relates to vacuum tube oscillators and more particularly to means for stabilizing the performance of such oscillators under varying conditions of power supply voltage.

One of the principal methods of generating high frequency electric currents, particularly in the ultra-high and micro-wave frequency regions, is by the use of a self-excited type oscillator having a cavity resonator, coaxial transmission line, or other high Q resonant circuit. These oscillators have a high degree of reliability, can be easily and inexpensively constructed, and are small in size. In addition, they may be readily constructed to operate to extremely high frequencies where other oscillator types have not been found practical.

One requirement of a satisfactory high frequency oscillator is that a high degree of frequency stability be achieved inasmuch as frequency disturbances considerably influence the performance of the radio, radar, or other equipments connected thereto. One of the factors influencing the frequency of operation of a self-excited oscillator is the voltage applied to the filament and plate circuits of the tubes since variations in these supply voltages alter the effective tube characteristics and thereby change the frequency of operation. In order to avoid these disturbances it has been common practice to use regulated power supplies for supplying these voltages, units which add substantially to the weight and space requirements of the oscillator and increase the expense thereof.

It is an object of my invention to provide improved means of stabilizing the frequency of self-excited oscillators.

An additional object of my invention is to stabilize the performance of a self-excited oscillator without regulating both filament and plate voltage supplies thereof.

It is a further object of my invention to stabilize the performance of an oscillator in a manner whereby standard, low cost, circuit components may be used and a maximum degree of simplicity and reliability obtained.

A further additional object of my invention is to stabilize the performance of a self-excited oscillator in a manner which does not require control of low voltage, high current, filament power supplies.

Still another object of my invention is to stabilize the performance of an oscillator even though power supply disturbances which would otherwise vary the oscillating frequency take place at a rapid rate.

2

Briefly, my invention resides in preventing frequency disturbances associated with power supply voltage changes in self-excited oscillators by providing a compensating change in some other power supply potential. That is, if a particular change in filament supply voltage produces a frequency disturbance of, say, 1 kc., I change the plate supply voltage an amount sufficient to produce a 1 kc. frequency change in the opposite direction, thereby compensating for the initial change in filament supply voltage and achieving a stable oscillating frequency.

Further, I stabilize the performance of a self-excited oscillator under rapidly changing filament supply voltage conditions by the use of a regulator which produces a plate voltage change in amount sufficient to maintain constant frequency but having a time delay equivalent to the thermal time delay inherent in the tube construction. That is, if the time interval between a filament voltage change and the corresponding changes in interelectrode capacitance, and other tube characteristics may be represented by an equivalent time constant of four seconds, I apply a plate circuit voltage controller having a time constant of four seconds, thereby causing the plate voltage change accurately to follow variations in tube characteristics.

The novel features which I believe to be characteristic of my invention are set forth with particularity in the appended claims. My invention itself, however, both as to its organization and method of operation together with further objects and advantages thereof may best be understood by reference to the following description taken in connection with the accompanying drawings in which Fig. 1 is a cross section view and partial schematic diagram of a stabilized high frequency system embodying the invention and comprising a conventional microwave oscillator utilizing a "lighthouse" tube in combination with a rectifying and voltage regulating circuit; Fig. 2 shows the equivalent circuit of the oscillator portion of Fig. 1; Fig. 3 shows the relationship between the frequency of oscillation and the cathode heating current for an oscillator such as that of Fig. 1 when operating under typical conditions; Fig. 4 shows the relationship between the frequency of oscillation and the plate voltage for an oscillator such as that of Fig. 1 when operating under typical conditions; Fig. 5 shows the relationship between cathode heating current and plate voltage for constant operating frequency for an oscillator such as that of Fig. 1; Fig. 6 is a detailed schematic diagram of the

rectifying and voltage regulating circuit illustrated in block form in Fig. 1, whereby oscillator operation in accordance with the principles of my invention may be achieved; and Fig. 7 is a group of curves further illustrating a mode of operation of my invention.

Referring now to Fig. 1, there is illustrated a typical microwave oscillator structure 12 in which a coaxial transmission line 1 is connected across grid 4 and cathode 5 of "lighthouse" tube 8 and a coaxial transmission line 2 is connected across grid 4 and anode 3 of the same tube. Direct plate supply voltage is impressed upon a pair of terminals 7, connected to anode 3 and to transmission line 2, respectively, from a rectifying and voltage regulating circuit 30. The circuit 30 is supplied from an alternating current supply source, not shown but indicated conventionally by terminals 15. The heater 9 may be supplied with cathode heating current from the same supply source through filament transformer 31 and a pair of terminals 6 connected directly to heater 9.

While the oscillator shown in Fig. 1 comprises a pair of coaxial transmission lines, its performance may be represented by an equivalent circuit comprising a modified tuned plate-tuned grid oscillator having a grounded grid. This equivalent circuit is shown in Fig. 2. It consists of parallel resonant circuit 10 representing coaxial transmission line 1 and parallel resonant circuit 11 representing coaxial transmission line 2. The grid-anode capacity of tube 8 is represented schematically by condenser 13 whereas the grid-cathode capacity is represented by condenser 14.

The frequency of oscillation of the oscillator circuit shown in Figs. 1 and 2 is determined by a number of factors including, in particular, the tube characteristics of interelectrode capacity and equivalent space path resistance. These characteristics alter the circuit impedances and therefore the natural frequency of oscillation of the system. Any external disturbances such as changes in heater voltage and current, plate voltage, etc., which alter the values of these tube characteristics, cause a corresponding change in the frequency of operation of the oscillator. If the heater current I_h applied to the tube is changed, for instance due to fluctuations in heater supply voltage, the temperature of the cathode, and consequently the physical size thereof, is altered from the normal condition. This changes both the tube grid-cathode capacitance and the effective space path resistance, thereby altering the frequency of oscillation. The magnitude and direction of this frequency change with variation in I_h is shown in Fig. 3 for the case of an oscillator such as that of Fig. 1 and having all other operating conditions held constant.

Fig. 4 shows the change in frequency of an oscillator such as that of Fig. 1 for various plate voltages E_b , all other circuit values being held constant. In this case, the plate voltage variations alter the effective space path resistance between the grid and anode and, to a limited degree, influence the operating temperature of the tube. Consequently a variation in oscillating frequency somewhat similar to that caused by changes in heater current takes place.

Combinations of plate voltage and heater current provide substantially constant oscillating frequency, the variations in one of these values compensating for the variation due to the other. These values may be plotted on a curve which I

prefer to designate the "constant frequency" curve of the oscillator. This curve, for the typical oscillator similar to that shown in Fig. 1, is shown in Fig. 5.

While the above-discussed frequency changes associated with variations in heater current and plate voltage are considered only with reference to the self-excited "lighthouse" tube oscillator, a similar effect takes place in other types of oscillators as well. A detailed discussion of observed disturbances on other self-excited oscillators at medium radio frequencies is given by Y. Kusonose and S. Ishikawa, in Frequency Stabilization of Radio Transmitters, Proc. I. R. E., vol. 20, p. 310, February 1932. As described in this paper, the frequency variations with other oscillators are similar to those shown in Figs. 3 and 4 herein.

One method of achieving oscillator operation along the constant frequency curve is to control the plate supply voltage in relation to the cathode heating voltage. If the same source is used for both of these voltages, as shown in Fig. 1, this can be achieved by incorporating a voltage regulator in circuit 30 which varies the applied plate voltage in response to the source voltage, the plate voltage following the curve of Fig. 5 in response to source voltage changes. Alternatively, the cathode heating current can be controlled to follow plate supply voltage changes, the cathode heating current varying in accordance with Fig. 5 as plate supply voltage changes takes place. In this case, the voltage regulator would of course be included in the cathode heater connections to terminals 6.

In general, I prefer to regulate plate supply voltage in accordance with cathode heating voltage changes for the reason that low current, small size regulating equipment may be used and no unavoidable time delays exist in the regulating circuit.

Fig. 6 shows one circuit arrangement of the rectifying and regulating circuit 30 whereby oscillator operation in accordance with my invention may be achieved. This circuit is described in detail in my Patent 2,247,082, the discussion of which is incorporated herein by reference. Briefly, the regulating circuit comprises tubes 16 and 17, together with gas discharge tube 18. The grid potential at tube 17 is determined both by the output voltage of filter 19, acting through potentiometer 20 and variable resistance 21, and by the output voltage of the plate voltage supply system acting through potentiometer 22 and variable resistance 23. The grid potential of tube 17, as compared to relatively constant voltage drop of gas discharge tube 18, determines the grid bias of tube 17 and the flow of space current therethrough, thereby establishing the voltage drop in resistance 25 and the grid voltage of tube 16. Inasmuch as the grid potential of tube 16 determines the voltage drop in the space path of this tube, the output voltage across terminals 7 is established by this grid potential. By proper choice of tubes 16, 17 and 18, together with the values of resistances 20, 21, 22 and 23, the output voltage across terminals 7 may be made to have any desired variation with respect to the value of output voltage from filter 19. As this voltage is proportional to power supply voltage at terminals 15, and the heater voltage across terminals 6 is likewise proportional to the power supply voltage at terminals 15, the plate supply voltage appearing across terminals 7 varies in accordance with the filament current. By properly choosing the circuit constants, this variation

may be made to follow a curve such as that shown in Fig. 5, thereby achieving constant frequency operation of the oscillator.

The frequency changes associated with heater current deviations shown in Fig. 3 do not take place instantaneously after a sudden change in heater supply voltage, but are delayed an amount determined by the thermal time constant and emission characteristics of the cathode. That is, if a sudden change in heater current to a value giving a particular frequency change takes place, the actual frequency change will not occur until some time after the constant change. This is shown in the curves of Fig. 7. Fig. 7 (a) shows a sudden change in cathode heating current i_t ; whereas Fig. 7 (b) shows the resulting variation in cathode temperature T . It will be observed that there is a time delay t_1 before the temperature reaches a new steady state value. Therefore, the frequency, as shown in Fig. 7 (c), has a corresponding time delay t_2 in reaching a new steady state condition equal to that of Fig. 7 (b).

In order to cause the plate supply voltage to follow the curve of Fig. 5 at all times after a sudden heater current change such as that shown in Fig. 7, it is necessary to delay the plate voltage change in accordance with the actual variation of the oscillator frequency. Hence, the plate supply voltage change should not suddenly take place but should follow a delayed curve such as is shown in Fig. 7 (d). This is shown in Fig. 7 (d) where the plate supply voltages required to compensate for the frequency change of Fig. 7 (c) are plotted.

Automatic time delay may be achieved in the voltage regulating circuit of Fig. 6, for instance, by the use of a condenser 24 connected to the grid of tube 17. Since this condenser opposes any sudden change in the voltage across its terminals, the voltage regulating action appearing at terminals 26 is delayed. By proper choice of the capacity of condenser 24 in relation to the value of resistances 21 and 22, the time constant of the complete voltage regulating circuit may be made to correspond with the effective time constant of the cathode of the oscillator tube, thereby causing the plate supply voltage to follow the curve of Fig. 5 at all times.

For purposes of explanation I have described operation of an oscillator along the constant frequency curve of Fig. 5. Most of the benefit of my invention can be achieved, however, by operating close to this line rather than attempting exactly to match it. Within reasonable limits, for instance, the curves of Figs. 3 and 4 can be approximated by straight lines, thereby making the approximate curve corresponding to Fig. 5 a straight line also. If operation along this straight line is achieved, frequency errors will be second order effects and of little importance for most purposes. It is, therefore, only necessary that the anode and cathode heating voltages substantially follow the constant frequency curve.

Although I have described above and regard as most practical the regulation of plate supply voltage in accordance with heater current, it will be apparent to those skilled in the art that stabilized oscillator control may be achieved by the reverse process. In this case a controller responsive to plate voltage and adapted to vary heater current in substantial accordance with Fig. 5 is provided, thereby maintaining substantially constant frequency operation.

While I have shown and described my inven-

tion as applied to a particular system of connections and as embodying various devices diagrammatically shown, it will be obvious to those skilled in the art that changes and modifications may be made without departing from my invention, and I, therefore, aim in the appended claims to cover all such changes and modifications as fall within the true spirit and scope of my invention.
